UNITED STATES PATENT OFFICE.

PAUL MARTIN, OF ROUBAIX, FRANCE.

HOLDER FOR PRINTING-SURFACES.

1,022,323.

Specification of Letters Patent.

Patented Apr. 2, 1912.

Original application filed August 16, 1910; Serial No. 577,427. Divided and this application filed April 15, 1911. Serial No. 621,385.

To all whom it may concern:

Be it known that I, PAUL MARTIN, a citizen of the French Republic, and residing at Rue du Fontenoy, Roubaix, France, have 5 invented certain new and useful Improvements in and Relating to Holders for Printing-Surfaces, of which the following is a specification.

The present invention relates to holders 10 for printing surfaces, and is more especially adapted for use in connection with the stereotype cylinders of cylindrical printing presses, and if so desired may be applied to the cylindrical printing press described in 15 my specification No. 577,427 filed August 16, 1910.

The invention consists in providing at 20 each end of the stereotype cylinder a flat circular plate mounted co-axially with the said cylinder, and holders having screwed shanks on which nuts are threaded being provided, the said nuts being held between the end plates of the cylinders and the above mentioned flat circular plates.

25 Referring to the drawings, Figure 1 is a plan of a stereotype cylinder, Fig. 2 is an end view of Fig. 1, and Figs. 3 and 4 show a plan and elevation of one of the holders.

30 The stereotype cylinder is constituted by a cylinder *a*, carrying at each end and mounted co-axially therewith a flat circular plate, *b*. A number of grooves are arranged longitudinally in the surface of the cylinder *a*, and holders *c* are adapted to slide in the said slots. The holders have 35 screwed shanks *d*, formed integral therewith, and nuts, *e*, threaded on the said screws. The shanks are held between the ends

of the cylinder and the plates *b*, through 40 holes in which, and arranged opposite to the grooves formed in the surface of the cylinder *a*, the shanks *d* project. By this means, when the nuts are rotated, the holders are translated along the grooves in the cylinder 45 *a*. The said holders serve to retain on and adjust the position of, the stereotype plates on the cylinder *a*, and moreover they are capable of a somewhat extensive displacement on the said cylinder, for allowing the 50 insertion of stereotype plates of different dimensions. Abutments may be placed at *f* for facilitating the insertion of divided stereotype plates.

Having now described my invention what 55 I claim as new and desire to secure by Letters Patent is:—

In a stereotype cylinder, cylindrical portions of reduced diameter at each end of said cylinder, circular end plates carried by said 60 reduced portions, so as to form an annular space between each end of the cylinder and the adjacent plate holders for retaining and adjusting the stereotype plate sliding in 65 slots in said cylinder, screwed shanks integral with said holders and passing through the end plates, and nuts threaded upon said shanks and held wholly within the annular space between the cylinder and the end plates.

70 In testimony whereof I have signed my name to this specification in the presence of two subscribing witnesses.

PAUL MARTIN.

Witnesses:

JANE PIERS,
J. LEFEVE.
